UNITED STATES PATENT OFFICE.

FRANK SAUNDERS HOLT, OF MONTGOMERY, ALABAMA.

TIKE-TIGHTENER.

SPECIFICATION forming part of Letters Patent No. 417,322, dated December 17, 1889.

Application filed October 15, 1889. Serial No. 327,073. (No model.)

To all whom it may concern:

Be it known that I, FRANK SAUNDERS HOLT, a citizen of the United States, residing at Montgomery, in the county of Montgomery and State of Alabama, have invented certain new and useful Improvements in Tire-Tighteners, of which the following is a description, reference being had to the accompanying drawings, and to the letters of reference marked thereon.

My invention is an improved tire-tightener of the type in which the tightening devices act between the spoke and the felly, as distinguished from that class in which they act simply between contiguous sections of the felly.

Heretofore various means have been devised for accomplishing the purpose of this invention; but all are more or less defective in operation, either from their complexity or by reason of the exposure of their working parts, thus allowing dirt and water to enter and interfere with their proper action. In addition to these, other defects peculiar to the particular class of tighteners to which this invention relates exist, viz: the material weakening of the spokes to which the tightening device is secured and the tendency of the parts to work loose.

The object, therefore, of the present invention is to construct a device which shall be simple and cheap in construction, unexposed in those parts which would be affected by dirt or moisture, and so attached to the spoke as not to weaken the same in the slightest degree.

The invention therefore consists in the construction and arrangement of parts whereby the above-mentioned objects are accomplished, and is illustrated in the accompanying drawings, in which—

Figure 1 is a side elevation of a portion of a wheel and spoke, showing my device in position. Fig. 2 is a similar view, partly in section. Fig. 3 is a side elevation of the spoke to which my invention is attached. Figs. 4 and 5 are side elevations of the upper and lower nuts, respectively. Figs. 6 and 7 are plan views of the same.

In the drawings, A is a section of the felly of a wheel, B the tire thereon, and C a spoke.

In the drawings the device is shown as applied to one spoke only; but it will be understood that as many of the spokes of a wheel are to be fitted with the tighteners as is found necessary to insure the best results.

The spoke C is preferably, though not necessarily, formed as shown in Fig. 3, consisting of a main portion *a*, a slightly-reduced portion *b*, and a tenon *c*, adapted to enter the felly B. This tenon may be of such length as to extend entirely through the felly, or, as will be apparent, may extend only part way through the same. The upper part of the reduced portion *b* of the spoke is preferably rounded for the reception of a nut D, (shown in Figs. 4 and 6,) said nut being thereby free to turn on said part *b*. The lower part of said reduced portion *b* is not rounded, but preferably hexagonal in form, in order to receive a nut E, (shown in Figs. 5 and 7,) the opening in which is of similar form, whereby said nut will be incapable of rotation. The nuts D and E are in external diameter preferably equal to the diameter of the spoke, and when in position the top of the nut D bears against a washer *d*, resting against and protecting the under side of the felly. Thus any upward movement of said nut will press the felly outward and increase its diameter, thereby tightening the tire.

It will be apparent that the washer *d* may be dispensed with and the nut bear directly against the under side of the felly. In order to provide for the upward movement of the nut D when it is desired to tighten the tire, the nut E has two inclined or cam surfaces formed upon its upper face, each incline extending over one-half of the surface and having sloping teeth formed on said inclines, as illustrated in the drawings.

The lower face of the nut D has corresponding inclines provided with teeth, so that when the two nuts are placed together in position on the portion *b* of the spoke they will form a perfect cylinder, fitting snugly at the top against the washer *d* and at the base against the shoulder on the main portion *a* of the spoke. When, however, the tire becomes slack and it is desired to tighten the same, it is only necessary to rotate the nut D, when the same will ride upon the inclined surface

of the nut E, and thus force out the felly, any backward rotation of the nut D being prevented by reason of the sloping teeth upon the inclines. The periphery of the nut D is 5 preferably provided with holes for the reception of a spanner; but it may be slightly flattened or otherwise adapted for the reception of a wrench to enable it to be readily rotated.

In order to protect the working parts from 10 the action of dirt and moisture, a sleeve S is provided fitting tightly over said parts, preferably covering completely the nut E, and leaving only enough of the nut D exposed to admit of the application of the tool for rotating it.

It will be seen that by making the teeth upon the inclined surfaces of the nuts sloping they can be readily forced apart in the forward rotation of nut D, but cannot come together again unless said nut is turned a little more than half-way around, when it will fall back into its original position.

The inclination of the inclined or cam surfaces of the nuts is preferably about enough 25 to lengthen the spoke one-fourth of an inch, when the nut D is turned one-third around, and it will be seen that by placing this device upon a number of the spokes the slackest tire can be tightened.

30 It will be apparent that the lower part of the reduced portion b of the spoke may be rounded instead of hexagonal, in which case it would be necessary to secure the nut E from rotation by securing it to the spoke in any 35 suitable manner. Again, the nut E might be dispensed with and toothed cam-faces corresponding to those on the nut D might be secured directly to the shoulder on the main portion of the spoke.

40 Numerous other changes from the particular construction herein shown and described might be made without departing from the spirit of my invention.

Having thus described my invention, what 45 I claim, and desire to secure by Letters Patent, is—

50 1. In combination with the felly of a wheel and a spoke fitting at one end therein, an annular toothed cam secured around a portion of said spoke, and a nut provided with a correspondingly-toothed cam on its lower face and located between said cam and the felly and adapted when turned to bear against said felly.

2. In combination with the felly of a wheel 55 and a spoke fitting at one end therein, a stationary ring or nut secured around said spoke and having two toothed cams or inclines formed upon its upper surface, each extending over one-half the surface thereof, 60 and a rotatable nut above the same, having its lower face formed to register with said stationary nut and located between the latter and the felly.

3. In combination with the felly of a wheel 65 and a spoke fitting at one end therein, a stationary nut secured around said spoke, having a toothed cam or cams on its upper face, and a rotatable nut between said stationary nut and the felly and correspondingly shaped 70 on its lower surface and adapted when rotated to bear against the felly.

4. In combination with the felly of a wheel and a spoke fitting therein, an annular toothed cam surrounding a portion of said spoke, a 75 nut having a correspondingly-toothed cam on its lower face and located between said cam and the felly, and a removable sleeve for inclosing the working parts.

5. In combination with the spoke and felly 80 of a wheel, a stationary nut surrounding said spoke, having a toothed cam or cams on its upper face, a rotatable nut between said stationary nut and the felly and correspondingly shaped on its lower face, and a removable 85 sleeve upon said spoke for inclosing the working parts, substantially as described.

6. The combination, with the felly and a spoke tenoned at its end to fit within the same and having a main portion a and a reduced portion b, said reduced portion being rounded at its upper part and hexagonal at its lower part, of a nut fitting around said hexagonal portion and having two toothed cams formed upon its upper surface, each extending over one-half the surface thereof, and a rotatable nut upon the rounded portion of said part b, having toothed cams registering with those on the lower nut, all substantially as described.

100 In testimony whereof I affix my signature in presence of two witnesses:

FRANK SAUNDERS HOLT.
